UNITED STATES PATENT OFFICE.

OSCAR JANELLE, OF MANCHESTER, NEW HAMPSHIRE, ASSIGNOR TO DRAPER COMPANY, OF HOPEDALE, MASSACHUSETTS, A CORPORATION OF MAINE.

AUTOMATIC FILLING-REPLENISHING LOOM.

951,949.

Specification of Letters Patent. Patented Mar. 15, 1910.

Application filed October 19, 1909. Serial No. 523,489.

To all whom it may concern:

Be it known that I, OSCAR JANELLE, a citizen of the United States, and resident of Manchester, county of Hillsboro, State of 5 New Hampshire, have invented an Improvement in Automatic Filling-Replenishing Looms, of which the following description, in connection with the accompanying drawing, is a specification, like characters on the 10 drawing representing like parts.

Looms of the "Northrop" type, in which the working shuttle is provided automatically with a fresh filling-carrier or bobbin when the filling needs to be replenished, are 15 so constructed that the incoming, fresh bobbin ejects the spent bobbin from the bottom of the shuttle and through a slot in the bottom of the shuttle-box in which slot the picker-stick oscillates. To guide the ejected 20 bobbin into a suitable receptacle the cut away or slotted part of the lay has been provided with an inclined chute having a part thereof upwardly extended beyond and crossing the inner end of the path of the picker- 25 stick, substantially as shown and described in United States Patent No. 596,448, granted to J. H. Northrop December 28, 1897. Between the guide-chute and the outer end 30 of the slot the picker-stick oscillates, and as filling-replenishment is effected when the picker-stick is at the outer end of its stroke there is an open or exposed portion of the slot between the stick and the chute when a 35 bobbin will drop into such exposed part of the slot and jam the picker-stick on its next inward stroke, causing more or less damage.

My present invention has for its object the production of means to guard or substantially cover the part of the slot referred 40 to when the picker-stick is at the outer end of its stroke, so that when a change or replenishment of filling is effected the ejected bobbin cannot enter the slot. I have so arranged the guard that it is engaged by and 45 moved out of the path of the picker-stick on the inward stroke of the latter and released shortly before the stick completes its outward stroke, so that the guard returns automatically to its protective position. At such 50 time the slot guard or protector is inclined downward and forward, so that if the tip of an ejected bobbin strikes it it will be directed forward in the general direction determined by the guide chute.

55 The novel features of my invention will

be fully described in the subjoined specification and particularly pointed out in the following claims.

Figure 1 is a front elevation of one end of the lay of a loom, at the replenishing side, 60 with the shuttle-box thereon and the guide-chute, one embodiment of my present invention being illustrated in connection therewith, the picker-stick being shown at the outer end of its stroke; Fig. 2 is a transverse 65 section on the line 2-2, Fig. 1, looking toward the left; Fig. 3 is an inner end elevation of the movable guard, shown by dotted lines in position to permit the passage of the picker-stick.

The lay A, the shuttle-box B thereon at the replenishing side of the loom, the race-plate C longitudinally slotted at D for the picker-stick E and to permit the discharge of an ejected bobbin through the bottom of 70 the shuttle, the cut-away or slotted part A^x of the lay below the slot D, and the guide-chute F fixedly secured to the front of the lay below the slot and having a part F^x upwardly extended beyond and crossing the 75 inner end of the path of the picker-stick, may be and are all substantially as in the Northrop patent hereinbefore referred to, and operate as therein set forth. The casting G, rigidly attached to the lay and which 80 serves as a support for the chute F, has a forward shelf or projection H, in practice sustaining a guide for the picker check-strap I, Fig. 1, substantially as in said patent, and upon this projection H I secure, by 85 a bolt 1, the slotted foot 2 of a bracket 3 having parallel, forwardly extended ears 4 for a pivot-pin 5, upon which pin is fulcrumed the hub 6 of the slot guard or protector. Herein the guard is shown as an 90 elongated piece of plate-metal 7, secured to or forming a part of the hub 6, and extended inward near the edge of the upwardly 95 extended part F^x of the chute, the guard being curved downward and forward along its 100 upper edge, as at 8, at its outer end, to cross the path of the picker-stick when the guard is in the position shown in Figs. 1 and 2, and in full lines Fig. 3. When the picker- 105 stick is at the outer end of its stroke, Fig. 1, it is at some distance from the cam portion 8 of the guard, the latter then resting upon the upturned back 9 of the bracket 3, see full lines Fig. 3, and covers or protects the 110 picker-stick slot beyond the part F^x of the

chute F. Should an ejected bobbin drop onto the inclined guard 7 it will be thrown forward away from the lay, and into a suitable receptacle, not shown, a diagonal, up-
 5 right ledge 10 on the guard preventing end-
 wise movement of the bobbin toward the
 end of the lay. When the picker-stick
 swings inward it engages the cam 8 and
 10 presses the guard 7 forward, the latter rock-
 ing on its fulcrum 5, and the picker-stick
 sweeps along behind the guard, holding the
 latter out of the way until on its outward
 15 stroke the picker-stick leaves the guard,
 which drops back of its own weight into
 guarding position. Stops 11 on the front of
 the bracket 3 limit forward movement of
 the guard, so that it cannot swing over its
 20 fulcrum.

In order to reduce wear between the
 25 picker-stick and the guard I prefer to back
 the latter with a facing 12 of leather, raw-
 hide, or other suitable material.

The dotted line position of the guard in
 Fig. 3 is that assumed when engaged and
 25 swung forward by the picker-stick, and as
 will be manifest such position is maintained
 during the major portion of the movement
 of the picker-stick.

Having fully described my invention,
 30 what I claim as new and desire to secure by
 Letters Patent is:—

1. The combination, in a loom having a
 lay longitudinally slotted for the passage
 of a filling-carrier ejected from the shuttle,
 35 a picker-stick reciprocating in the slot, and
 a guide-chute beyond and crossing the inner
 end of the picker-stick path, of means governed
 by the picker-stick to prevent the passage
 40 of an ejected filling-carrier through
 the slot between the chute and picker-stick
 when the latter is at the outer end of its
 stroke.

2. The combination, in a loom having a
 lay longitudinally slotted for the passage
 45 of a filling-carrier ejected from the shuttle,
 a picker-stick reciprocating in the slot, and
 a guide-chute beyond and crossing the inner
 end of the picker-stick path, of a movable
 50 guard to close the slot beyond the chute
 when the picker-stick is at the outer end of
 its stroke, the picker-stick coöperating with
 the guard to temporarily move it out of the
 path of the stick.

3. The combination, in a loom having a
 55 lay longitudinally slotted for the passage of
 a filling-carrier ejected from the shuttle, a
 picker-stick reciprocating in the slot, and a
 guide-chute beyond and crossing the inner
 end of the picker-stick path, of a swinging
 60 guard pivotally mounted on the lay and ex-
 tending laterally from the chute, to protect
 the exposed part of the slot from the en-
 trance of a filling-carrier, a cam on the
 guard to coöperate intermittently with the

picker-stick and move the guard forward 65
 out of the path of the picker-stick, and
 means to limit swinging movement of the
 guard.

4. In a loom, a longitudinally-slotted lay,
 the picker-stick movable therein, and a fixed 70
 guide-chute on the lay and extended upward
 and across the inner end of the path of the
 picker-stick, combined with a guard pivoted
 on the lay and adapted to prevent the en-
 trance of an ejected filling-carrier into the 75
 slot beyond the chute, and a cam on the
 guard to coöperate intermittently with the
 picker-stick and effect movement of the
 guard out of the path of the picker-stick.

5. In a loom, a lay provided with a shut-
 tle-box having a longitudinally-slotted bot-
 tom for the discharge of a filling-carrier
 ejected from the shuttle, said lay being slot-
 ted below the shuttle-box, a picker-stick 80
 movable in the slot, an inclined slot-protect-
 ing member fixed on the lay at the inner
 end of and crossing the path of the picker-
 stick, a movable slot-protecting member
 85 pivoted on the lay to guard the slot beyond
 the fixed member, the movable member en-
 tering the major part of the picker-stick
 path when the stick is at the outer end of
 its stroke, a stop to retain said movable
 member in inclined position at such time,
 90 means on the movable member to intermit-
 tingly coöperate with the picker-stick and
 effect movement of the said member out of
 the path of the picker-stick.

6. In a loom, a lay provided with a shut-
 tle-box having a longitudinally-slotted bot-
 tom for the discharge of a filling-carrier
 ejected from the shuttle, said lay being slot-
 ted below the shuttle-box, a picker-stick 100
 movable in the slot, an inclined slot-protect-
 ing member fixed on the lay at the inner
 end of and crossing the path of the picker-
 stick, and automatically-movable means to
 105 protect the slot beyond said member when
 the picker-stick is at the outer end of its
 stroke and to move out of the path of the
 picker-stick on its inward stroke.

7. In a loom, a lay slotted for the dis-
 charge of a filling-carrier when ejected from
 the shuttle, a picker-stick movable in the
 slotted part of the lay, a guide-chute for
 the ejected filling-carrier, extended beyond
 115 and crossing the inner end of the path of
 the picker-stick, and means to prevent the
 passage of an ejected filling-carrier into
 the slot beyond the guide-chute.

In testimony whereof, I have signed my
 name to this specification, in the presence
 of two subscribing witnesses.

OSCAR JANELLE.
